UNITED STATES PATENT OFFICE.

CHARLES R. SAUNDERS, OF RICHMOND, VIRGINIA.

HEAD-REST FOR CAR-SEATS.

1,083,633.

Specification of Letters Patent.

Patented Jan. 6, 1914.

Application filed August 26, 1912. Serial No. 717,101.

To all whom it may concern:

Be it known that I, CHARLES R. SAUNDERS, a citizen of the United States, residing at Richmond, in the county of Henrico, State 5 of Virginia, have invented certain new and useful Improvements in Head - Rests for Car-Seats; and I do hereby declare the following to be a full, clear, and exact description of the invention, such as will enable 10 others skilled in the art to which it appertains to make and use the same.

This invention relates to certain novel and useful improvements in head rests for car seats, and has particular application to a 15 device of this class adapted to be applied to the backs of the car seats of day coaches and railway trains, the seats of interurban trolley cars and the like.

In carrying out my invention it is my 20 purpose to provide a simple, cheap and efficient type of head rest which may be readily and quickly applied to and removed from the back of the seat and which is so compact and composed of such relatively 25 few parts that it may be conveniently handled by the passenger or porter.

Furthermore, I propose to manufacture 30 my head rest of sections of flexible or resili- 35 ent material such, for instance as spring metal, the parts being so assembled and cor- related that the rest will readily yield or accommodate itself to any movement of the head of the passenger, so that while it forms a comfortable rest, it will at all times 40 efficiently perform its supporting function irrespective of the position of the head resting thereon.

With the above recited objects and others of a similar nature in view, my invention 45 consists in the construction, combination and arrangement of parts set forth in and falling within the scope of the appended claims.

In the accompanying drawings: Figure 1 50 is a perspective view showing my head rest applied to the back of a seat, such back being shown in dotted lines. Fig. 2 is a view in side elevation.

Referring now to the accompanying 55 drawings in detail, the letter A designates the ordinary seat back, while B indicates my head rest as an entirety. This head rest comprises an inverted U-shaped clamping member 1 which is preferably formed of a strip or band of sheet metal possessing sufficient resiliency or spring to enable it to

be slipped over the edge of and clamped upon the back of car seats of different thicknesses or sizes. The front arm of the clamp is shown at 6, while the rear arm indicated at 7 is formed with a compound curve or 60 bend, so that the depressed section 9 of the arm will bind or bear against the rear face of the seat back.

The supporting standard or shank of the device is designated as a whole by the number 65 10 and is also preferably formed of a strip or band of sheet metal possessing the requisite resiliency and temper to enable it to yield readily when the head is resting upon the head plate 11, without such shank 70 breaking or being distorted or bent out of working position. This shank is constructed to have a lower section 12 which lies against and conforms to the shape of the front arm 6 of the clamp and is secured to 75 the latter by means of the rivets 13. Above the top of the clamp this supporting shank is bent to form the rearwardly extending longitudinally disposed U-shaped portion 14 and the upper, normally horizontally disposed arm 15 which projects forwardly of 80 this clamp and is curved downwardly as at 16 and thence upwardly at its terminal as at 17. To the end or terminal of the shank is pivoted as at 18 the head plate 11. As will 85 be seen by reference to the drawing this plate, which is also preferably formed of a strip of sheet metal capable of being bent if desired to accommodate it to the convenience of the wearer, is curved in approxi- 90 mately semicircular form so that it has the two oppositely extending end sections 19 which are adapted to bear against the base of the head at the sides thereof. This 95 curved plate it will be noted extends at its point of juncture with the arm 15 at right angles to the latter with the central section 20 of the plate normally lying in substantially a horizontal plane, while the arm 15 slopes upward and rearward from the central section of the curved plate. This is an 100 important feature of my invention, for when the device is in use and therefore the plate and arm slightly depressed, the neck and base of the head are supported by the plate, while the arm 15 in addition to forming a part of the shank for the plate also bears against and supports the central back portion of the head immediately above the base 105 of the latter. It will therefore be noted 110

that the head and neck are supported over a considerable area thus conducing to the comfort of the wearer. Furthermore, I wish to direct particular attention to the fact that 5 by my peculiar arrangement and construction of spring shank and curved head plate, the head and neck supporting parts thus formed will yield to the movement of the head of the passenger whether it be from 10 side to side or backward and forward, and yet will at all times immediately spring back or return to supporting position.

The front edge 21 of the curved head plate is turned or rolled as at 22 to avoid a sharp 15 cutting edge and to provide a smooth comfortable surface, against which the neck of the passenger may rest without inconvenience.

It will be noted that by constructing my 20 device as described I provide a head rest wherein the head plate is an approximately normally horizontally disposed curved plate in the nature of a strip supported upon the arm section of the supporting standard or 25 shank in such a manner that the shank itself at such arm portion forms an additional means for supporting the head.

While I have herein shown and described 30 one particular embodiment of my invention, I wish it to be understood that I do not confine myself to all the precise details of construction herein set forth by way of illustration as modification and variation 35 may be made without departing from the spirit of the invention or exceeding the scope of the appended claims.

What I claim is:

1. A device of the class described comprising an attaching member, a resilient supporting shank secured thereto and a plate 40 carried by the supporting shank, said plate and the adjacent portion of the shank being adapted to contact with and support the head.

2. The combination with an attaching 45 member, of a resilient supporting shank attached thereto and terminating in a section extending forwardly of the attaching member, and a head plate carried at the end of the forwardly extending portion of the 50 shank, said plate and forwardly extending shank section both being adapted to bear against and support the head.

3. The combination with a U-shaped attaching clamp, of a shank comprising a 55 lower portion conforming with and attached to the front part of the clamp, said shank being then bent to form a rearwardly extending U-shaped portion and a forwardly extending normally substantially horizontally disposed arm section which projects beyond the front of the clamp, and a curved head plate pivoted at its center to the end of the arm section transversely thereof, said head plate and arm section both forming 60 65 head supporting means.

In testimony whereof, I affix my signature, in presence of two witnesses.

CHARLES R. SAUNDERS.
